UNITED STATES PATENT OFFICE.

JAMES L. FRAZIER, OF PEORIA, ILLINOIS.

THILL-COUPING.

SPECIFICATION forming part of Letters Patent No. 683,926, dated October 8, 1901.

Application filed December 24, 1900. Serial No. 40,999. (No model.).

To all whom it may concern:

Be it known that I, JAMES L. FRAZIER, a citizen of the United States, residing at Peoria, in the county of Peoria and State of Illinois, have invented certain new and useful Improvements in Thill-Couplings; and I do hereby declare that the following is a full, clear, and exact description of the invention, which will enable others skilled in the art to which it appertains to make and use the same.

This invention pertains to thill-couplings, and has for its object to improve the construction and increase the utility of this class of devices.

In the drawings forming a part of this application and presented herewith, Figure 1 represents a side view, in part section, of my improved coupling attached to the axle of the vehicle, showing the eye of the thill connected therewith. Fig. 2 is a plan view of the same. Fig. 3 is a sectional view of a pair of pivoted jaws, showing a wedge entered between them. Fig. 4 is a plan view of a portion of the jaws shown in Fig. 3, showing the wedge. Fig. 5 is a perspective view of a portion of my improved thill-coupling with the jaws broken away to show a strengthening-stud. Fig. 6 is a perspective view of a stem which carries the wedge. Fig. 7 is an elevation in part section of a modified form of means for withdrawing the wedge from between the arms. Fig. 8 is a rear view of a portion of the same. Fig. 9 is also a modified form of means for withdrawing the wedge, the same being shown in cross-section.

In the several figures, A indicates the axle, and B the clip connecting the coupling with said axle and which is formed with the body of the coupling. The latter consists of an upper and lower horizontal lug C and D, respectively. Upon the upper lug is a barrel or lug E, which is formed with said upper lug and channeled out substantially as shown at F, such channel being cut parallel with the axle. The barrel and lug C are bored out, as shown in Fig. 1, at G, and such bore is carried through the lower lug D as well, all of which is shown in Fig. 1. The barrel above said bore G is provided with a square opening H for receiving a square stem I, carrying a wedge J at its lower end. The square stem and the opening therefor prevent the wedge turning

in the barrel, thereby keeping it in its proper operating position. Between the lugs C and D are pivoted two jaws K by means of pivots L, which pass through both lugs, as indicated by dotted lines in Fig. 1. The forward end of each jaw carries a tapered lug or head adapted to enter the eye N of the thill. These are arranged adjacent to each other and co-operate as described and shown. The rear extremities of the jaws are pointed and when lying adjacent to each other present the appearance shown in Fig. 4 in unbroken lines, and when separated appear as in dotted lines 65 in said figure and in Fig. 2 as well. In order to separate the jaws at the rear to carry their forward ends into engagement with the eye N, I provide a wedge J, Figs. 1, 3, and 4. The sides of the wedge and the adjacent portions 70 of the jaws are beveled at an angle, so that when the former is entered between the jaws movement of those members is prevented. The bottom of said wedge is pointed substantially as shown, so that when entering the 75 said beveled adjacent portions of the jaws separation is readily accomplished. The upper end of the stem I is round in cross-section and carries a cross-arm O, held between the shoulder formed at the top of the square 80 portion of the stem and a head P, formed with the latter, as shown. An opening-spring Q between the wedge and the barrel E at the top of the bore H serves to normally keep the wedge seated between the 85 jaws K. When occupying this position, the cross-arm O rests in the bottom of the channel F, as shown in Fig. 1. In order to raise the wedge, the cross-arm O is raised against the pressure of the spring and swung 90 at right angles to the channel against the pressure of the said spring and rests upon the top of the barrel. The rounded portion of the stem permits the cross-arm to turn, while the square portion, as above described, prevents 95 the wedge from turning, so that it is always in proper position for entering between the jaws. The rear ends of the jaws are recessed, as shown at R, Fig. 4, and a closing-spring R', attached to each jaw, draws the two rear ends 100 together when the wedge is raised, thereby separating the heads M and releasing the eye N.

I have indicated in Figs. 1 and 5 a post S between the outer extremities and the lugs C

and D; but this is merely to strengthen the parts and forms no part of my invention.

In Figs. 7, 8, and 9 I have shown modified forms of the coupling. In the first two figures an eccentric or cam is substituted for the cross-arm O. When in the position shown, the wedge is in engagement with the jaws below; but when thrown to the dotted-line position the wedge is raised. This constitutes a very convenient form of the device and is very effective when it is desired to make the coupling serve as a means of detaching the horse from the vehicle in case of accident or a runaway. By attaching suitable cords or wires to the arms of the cams they may be quickly raised to release the jaws. Evidently this may also be done with the form first described by using suitable means for accomplishing it. Fig. 8 is a view of the eccentric, showing the stem pivoted between its bifurcated extremity. Fig. 9 shows another form, in which a screw U and wedge at its lower end are made as an integral part. The wedge is conical in form and turns as it enters and leaves the jaws. The screw is entered from below when assembling the parts, and the upper end carries a thumb-piece by which to turn it.

In bringing out my invention I am aware that the lugs or heads M for engaging the eye of the thill are not new; but my peculiar form of the jaws that carry them and the means for locking and releasing them are new. I may vary the construction of the device or change the location of the parts or omit some of the minor elements without departing from the spirit or intent of my invention.

Having described my invention, I claim—

1. In a thill-coupling, the combination of the body thereof consisting of an upper and lower lug, jaws pivoted between the lugs and extending forward of and behind their pivotal points, the said forward ends carrying lugs, or heads for entering the eye of the thill and a wedge for engaging the rear ends of the jaws and adapted to enter between and separate them to cause the forward ends to approach one another to engage the thill as described.
2. In a thill-coupling, the combination of an upper and lower lug, a pair of jaws pivoted between them and adapted to swing horizontally on their pivots, the said jaws projecting forward, extensions on the said forward ends for entering the eye of the thill, said jaws extending rearwardly from their pivotal points, a vertically-operated wedge adjacent to such rear extensions and adapted to enter between them to separate said jaws to bring their forward ends into engagement with the thill at their forward ends, a barrel above the rear ends of the jaws for supporting the said wedge a spring for depressing the said wedge and means by which to withdraw

the wedge from between the jaws against the pressure of said spring substantially as set forth.

3. In a thill-coupling, the body comprising an upper and lower lug attached to the axle of the vehicle, a pair of jaws pivoted between the same and having forward and rearward extensions, the former for entering the eye of the thill, the latter adapted to be separated by means entered between them, a spring-actuated wedge for accomplishing such separation, means for supporting and guiding the wedge and means by which to raise and sustain said wedge above the jaws which consists of a cross-arm attached to and swiveled upon the top of the said supporting means substantially as set forth.

4. In a thill-coupling, a body consisting of an upper and lower lug attached to the axle of the vehicle, a pair of jaws pivoted between them the same extending forward of their points and having extensions to enter the eye of the thill, said jaws also projecting rearwardly, a spring at such rear ends adapted to bring such ends together when liberated, a vertically-moving wedge to enter between the jaws at the rear and separate them, a stem for supporting and guiding the wedge, a spring surrounding the stem, means by which to raise the stem and wedge against pressure of said spring, a swiveled cross-arm on the top of the stem, a channel in the supporting means for permitting such cross-arms to lie therein while the wedge is in engagement with the jaws all being arranged whereby the said cross-arm may be raised from the channel and thus raise the wedge the former adapted to be turned at right angles to the channel and rest upon the supporting means thus preventing the wedge entering between the jaws.

5. In a thill-coupling, a body consisting of lugs C and D, jaws K pivoted between them the same extending forward of their pivotal points, lugs or heads M at the forward ends for engaging the thill, the rear ends being beveled to permit them to approach each other to separate their forward ends, a spring between said rear ends for drawing them together, a wedge J for entering between and separating said rear ends, a stem I for carrying the wedge, a drum or barrel E for the stem, a spring Q surrounding the stem and lying between the said wedge and the drum for the purposes set forth, said stem adapted to raise the wedge and rest upon the said drum substantially as set forth and for the purposes described.

In testimony whereof I affix my signature in presence of two witnesses.

JAMES L. FRAZIER.
